CONTROL DEVICE FOR DRUM DRIER

Harold B. Wallis, Dayton, Ohio, assignor to General Motors Corporation, Detroit, Mich., a corporation of Delaware

Application November 4, 1953, Serial No. 390,204

1 Claim. (Cl. 34—53)

This invention relates to a domestic appliance and more particularly to laundry dryers.

Laundry dryers remove moisture from clothes. Some dryers dissipate this moisture into the air in the room where it may condense on cold walls and windows. Many owners complain of this and therefore a dryer has been made and sold in large quantities in which the moisture is condensed in the dryer instead of dissipating the moisture into the room. It has been customary to provide a removable collecting vessel for disposing of said condensed moisture. However, some owners neglect the emptying of this vessel and under such a circumstance eventually the collecting vessel will overflow into the room where it may do some damage.

It is an object of my invention to provide means for automatically removing condensed moisture from the dryer as it accumulates.

It is another object of my invention to provide an arrangement wherein the same timer which is used to control the starting and stopping of the fan, driving motor, and heater is also used to control the starting and stopping of a pump for pumping the condensed moisture from the dryer into a drain.

To attain this object I provide an additional cam and contacts in the timer arranged to close the circuit to a small electric motor which is directly connected to a small pump having a suction connection connected to the interior of the collecting vessel and its discharge conduit extending to a suitable drain.

Further objects and advantages of the present invention will be apparent from the following description, reference being had to the accompanying drawings wherein a preferred form of the invention is clearly shown.

In the drawing:

Figure 1 is a vertical sectional view partly diagrammatic of a condensing type laundry dryer embodying one form of my invention;

Figure 2 is a fragmentary side elevation showing the outlet of the pump connected to a laundry tub provided with a drain; and

Figure 3 is a chart showing the times when the blower and drum and the heater of the dryer are operated and also showing the period during which the pump is operated.

Referring now to the drawing and more particularly to Figure 1 there is shown a laundry dryer 20 including a drum casing 22 provided with a perforated rotatable drum 24. The clothes are placed within the drum 24 and the drum 24 is rotated by the electric motor 26 through a worm and worm wheel 28 and a belt 30. The clothes are heated by an electric heater 32 connected by the conductors 34 to one set of contacts upon the automatic timer 36. The motor 26 is connected by the conductors 38 to a second set of contacts upon the timer 36. The timer 36 is connected to the supply conductors 40.

The drum casing 22 is provided with small air inlet apertures 42 adjacent the heater 32. The drum casing

2

22 is also provided with a bottom outlet 44. Communicating with this bottom outlet 44 are the vertical passages of an air cooled condenser 46. The motor 26 is provided with a fan 48 for drawing cooling air through the condenser 46. When so cooled the condenser 46 condenses moisture driven out of the clothes in the drum 24. The condensed moisture is collected in the collecting vessel or tray 49 located directly beneath the condenser 46.

To avoid the necessity of manually emptying the vessel 49, I provide a small pump 50 having a suction inlet tube 52 extending to the bottom of the collecting vessel 49. The pump 50 also has an outlet conduit 54 extending out the back of the cabinet and provided at its upper end with a gooseneck metal member 56 which is hung over the edge of a laundry tub 58. The laundry tub 58 is provided with a suitable drain connection 60.

The pump is preferably of the Moyno rubber worm type such as is shown in Patent 2,527,673 issued October 31, 1950. It is driven by a $\frac{1}{100}$ H. P. electric motor 62. This motor is connected to the timer by the conductors 64 to an additional set of contacts provided in the timer 36. The timer as shown in the chart Figure 3 causes the operation of the fan and drum and heater throughout the entire operating cycle. Also, as shown in Figure 3, the contacts of the timer 36 which control the pump 62 are closed during the latter portion of the laundry cycle. I prefer that the pump be operated in this manner during the last $7\frac{1}{2}$ minutes of each laundry cycle to remove the condensate from the pan 49 and dispose of it to the drain.

In accordance with the provision of Rule 78a, reference is made to the following prior filed applications, S. N. 338,674 filed February 25, 1953, S. N. 298,566 filed July 12, 1952, and S. N. 217,618 filed March 26, 1951, now abandoned.

While the form of embodiment of the invention as herein disclosed constitutes a preferred form, it is to be understood that other forms might be adopted as may come within the scope of the claim which follows.

What is claimed is as follows:

40. A laundry dryer including a drum casing containing a rotatable drum, heating means for driving moisture out of laundry in the drum, an air cooled condensing means having one set of heat transfer passages in communication with the interior of the drum casing, fan means for circulating cooling air into heat exchange relation with said condensing means to cool the condensing means to condense moisture from the drum casing, collecting means for collecting condensed moisture from the condensing means, a pump for removing moisture from the collecting means, electrical operating means for said drum and said fan means, a separate electrical operating means for said pump, a timing device including a plurality of contact means separately connected to said electrical operating means for said drum and fan means and said heating means and said separate electrical operating means and timing means for closing said contact means at predetermined times to operate said drum and fan means and said heating means and to close a separate set of contacts connected to said separate electrical operating means for said pump after the beginning of the operation of said fan means and said heating means and before the termination of the operation thereof.
